(57) **CLAIM**

The ornamental design for a cell phone cover with sun shade, as shown and described.

DESCRIPTION

FIG. 1 is a front perspective view of a cell phone cover with sun shade showing a first embodiment of my new design;

FIG. 2 is a front view of the cell phone cover with sun shade shown in FIG. 1;

FIG. 3 is a rear view of the cell phone cover with sun shade shown in FIG. 1;

FIG. 4 is a left-side view of the cell phone cover with sun shade shown in FIG. 1;

FIG. 5 is a right-side view of the cell phone cover with sun shade shown in FIG. 1;

FIG. 6 is a top view of the cell phone cover with sun shade shown in FIG. 1.

FIG. 7 is a bottom view of the cell phone cover with sun shade shown in FIG. 1;

FIG. 8 is a front perspective view of the cell phone cover with sun shade shown in FIG. 1 with the sun shade in a partially open state;

FIG. 9 is a front perspective view of a cell phone cover with sun shade showing a second embodiment of my new design;

FIG. 10 is a front view of the cell phone cover with sun shade shown in FIG. 9

FIG. 11 is a rear view of the cell phone cover with sun shade shown in FIG. 9;

FIG. 12 is a left-side view of the cell phone cover with sun shade shown in FIG. 9;

FIG. 13 is a right-side view of the cell phone cover with sun shade shown in FIG. 9;

FIG. 14 is a top view of a cell phone cover with sun shade shown in FIG. 9;

FIG. 15 is a bottom view of the cell phone cover with sun shade shown in FIG. 9; and,

FIG. 16 is a front perspective view of the cell phone cover with sun shade shown in FIG. 9 with the sun shade in a partially open state.

The broken lines immediately adjacent the shaded regions represent the bounds of the claimed design. All other broken lines depict environmental subject matter that forms no part of the claimed design. The broken lines and unshaded regions bounded by broken lines form no part of the claimed design.
